UNITED STATES PATENT OFFICE.

SAMUEL M. DIXON, OF MILWAUKEE, WISCONSIN.

MACHINE FOR CUTTING CURVED SURFACES.

SPECIFICATION forming part of Letters Patent No. 409,024, dated August 13, 1889.

Application filed October 23, 1888. Serial No. 288,949. (No model.)

To all whom it may concern:

Be it known that I, SAMUEL M. DIXON, of Milwaukee, in the county of Milwaukee and State of Wisconsin, have invented certain new and useful Improvements in Machines for Cutting Curved Surfaces; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

The object of my invention is to produce a cut on a varying, irregular, or compound curve.

It consists, essentially, of a cutter susceptible of a variable curvature, together with mechanism for supporting, changing the curvature of, and guiding the cutter, suitable feeding and driving mechanism, means for supporting and holding the work in proper position, &c.

My invention is applicable to the manufacture from any suitable material of all manner of articles having curved faces—such as staves, chair backs and bottoms, carriage-panels, &c.—but for the purpose of illustration I have shown a machine designed particularly for sawing staves and like articles.

Referring to the accompanying drawings, in which like letters designate the same parts in the several figures, Figure 1 is a perspective view of a stave-sawing machine embodying my invention. Fig. 2 is a vertical longitudinal section of the same on the line $x x$, Fig. 3. Fig. 3 is an elevation of the right-hand end of the machine as viewed in Figs. 1 and 2. Fig. 4 is a cross-section on the line $y y$, Fig. 2, showing on an enlarged scale the vibrating saw-frame, curved saw-guides, and the shaft on which they are supported. Fig. 5 is a cross-section on the line $z z$, Fig. 4, of one of the arms of the saw-frame, showing in plan view one of the saw-holding blocks; and Fig. 6 is a side elevation, on an enlarged scale, of one of said blocks.

A represents a horizontal shaft, supported at the ends in standards $A' A^2$ or other suitable frame-work. Upon this shaft is mounted the vibrating cross-head B, to the ends of which are adjustably secured, at the desired

inclination thereto, the depending slotted arms $b b$, constituting, in connection with said cross-head, the saw-frame. On opposite sides 55 of said saw-frame are loosely mounted on said shaft A vibratory inverted-U-shaped cross-heads D D, to the depending ends of which are attached the removable guides or patterns D' D', parallel with the shaft A, so as 60 to pass lengthwise freely through the slots of arms $b b$. The patterns D' D' are formed to the desired curve on their upper edges, which have on each side laterally-projecting flanges d d.

C C are saw-holding blocks reduced to cylindrical form to fit between the four sections of arms $b b$, as shown in Figs. 4, 5, and 6, and to turn freely in boxes c c, which are placed over the cylindrical reductions of said blocks 70 and are fitted between opposite sections of said arms $b b$, as shown in Fig. 5. These boxes c c are divided axially and vertically to permit of their being placed in the grooves in said blocks C C, around the reduced cylindrical parts thereof, and are constructed to move freely up and down between the arms $b b$, by which they are held in place.

The blocks C C are formed near their inner ends with transverse cylindrical holes, open at 80 the sides through the ends of said blocks, as shown in Figs. 4 and 6. They are also formed, between the grooves therein, with transverse T-shaped openings, through which the flanged upper edges of the patterns D' D' pass. The saw 85 E is preferably serrated on both edges, so as to cut in both directions. It is secured at the ends in the sides of cylinders e e, which are fitted to and inserted in the transverse holes in said blocks C C, the saw passing through 90 the slotted openings in the ends of the blocks, as clearly shown in Fig. 4. The cylinders e e are retained in said blocks by screws and washers e' e', which overlap their ends, or by any other suitable means. They turn 95 freely in the blocks C C and permit of variation in the curvature of saw E as the blocks approach or recede in moving up and down in the arms $b b$.

The saw-frame is prevented from moving 100 lengthwise on the shaft A by a fixed sleeve a' on the standard A³, in which the hub of the cross-head B is retained by a nut b² or other suitable means, while the cross-heads D D,

carrying the patterns D' D', are free to move lengthwise of said shaft and partake of the vibratory movement of the saw-frame.

F is the driving-shaft supported in boxes 5 a a on standards A² A³, or other suitable supports, parallel with the shaft A. Upon this shaft are mounted the crank-wheel f, eccentric f², tight and loose pulleys f³ f⁴, and balance-wheel f⁵. The crank-wheel f is connected by the pitman f' with an arm b', projecting upwardly from the cross-head B. The pulleys f³ f⁴ are connected with any suitable source of power, and the eccentric f² is connected with the carriage-feeding mechanism 10 hereinafter described.

G is a carriage supported and adapted to be moved on suitable ways g g, parallel with the shaft A. To diagonally-opposite corners of said carriage are attached standards g' g', 20 formed at their upper ends with sleeves for the reception of the hubs of cross-heads D D, which are retained therein by nuts g⁴ g⁴, as shown in Fig. 2. By this means the patterns D' D' are caused to move with the carriage G.

H is a vertically-movable work-support provided with four cog-toothed legs or racks, which pass through mortises in the carriage G and engage with gears I I, by means of 25 which said work-support H is raised and lowered. These gears I I work together or intermesh in pairs on each side of the carriage, and the shafts on which they are mounted have bearings in and are movable with carriage G, as shown in Figs. 1, 2 and 3. One of 30 the shafts of the gears I is provided with a crank I', by means of which the work-support H is manually operated, and with a ratchet-wheel I², engaged by a pawl i, pivoted to the carriage for preventing the descent of 35 said work-support as it is raised. Any suitable mechanism, which will readily suggest itself, may be employed instead of the crank for automatically lifting the work-support H an interval at each reversal of the movement 40 of carriage G.

The work-support H is longitudinally slotted and provided with dogs h' h', one at each end, guided and adapted to move in the slots therein, as shown in Figs. 1 and 2. A screw-shaft h², provided at one end with a crank h³ for turning it, and journaled in the ends of 50 said work-support H, underneath and parallel with the slots therein, is formed with right and left screw-threads, one of which works 55 with a corresponding nut in one dog h', while the other works with a similar nut in the other dog. By turning the screw-shaft h² in one direction the dogs h' h' are caused to simultaneously approach each other toward the 60 center of the work-support H. Turning the screw-shaft in the reverse direction causes said dogs to recede in like manner toward the ends of said work-support. By this means 65 the block to be sawed or cut is always dogged in the center of the work-support and travel of the carriage.

Underneath the carriage G are journaled,

in suitable supports at or near the ends of said carriage, when the same is in its middle position, four chain-wheels K K, two side by side at each end. Upon these wheels are mounted two parallel endless chains k k, to which are secured the ends of a cylindrical cross-shaft k', as shown in Fig. 2. Upon the shaft k', between said chains, is mounted so 75 as to turn freely thereon a perforated block g³, held and adapted to move freely up and down in a vertical slot in the upright arm g², attached to the under side of the carriage G. Each chain-wheel K is mounted upon an independent shaft, so as to leave a clear space 80 between them for the passage of the arm g², as shown in Fig. 3.

At one end of the machine is supported in suitable bearings a cross-shaft l, upon which 85 are mounted two ratchet-wheels L L and two gear-wheels l' l', as shown in Figs. 1, 2, and 3. The gears l' l' engage with and drive the gears k², one mounted on each of the shafts 90 of the adjacent pair of chain-wheels K K.

N is a U-shaped pawl-carrier, hinged at its ends on the shaft l just outside of the ratchet-wheels L L. To the pawl-carrier N are pivoted pawls n n, adjacent to the ratchet-wheels L L, with which they are held in engagement 95 by the springs n' n', said springs allowing the pawls to slide over the teeth of the ratchet-wheels when the pawl-carrier descends. The pawl-carrier N is connected with and operated by the eccentric f² through the strap m and connecting-rod m', whereby the feed of 100 the carriage G is made to correspond and vary with the movement of the saw E, which is driven from the same shaft. The feed of said carriage is varied as desired by setting the 105 adjustable hub of the eccentric f² nearer to or farther from the center.

I do not wish to be understood as restricting myself to the precise construction and arrangement of mechanism hereinbefore described, inasmuch as it is susceptible of various changes and modifications within the 110 spirit and intent of my invention.

My improved machine operates as follows: Taking, for example, the machine shown in 115 the drawings, which is arranged to saw staves and the like, patterns D' D', of the required curvature, are employed to give the required longitudinal curvature to the stave. The arms b b are also set at the required inclination 120 to the cross-head B to produce, in co-operation with said patterns by gradual changes in the curvature of the saw, a cut of gradually-increasing curvature from the center toward the ends of the stave to correspond 125 with the distance from the axis of the barrel, &c., to any point in the length of the stave. The block to be sawed or cut is secured in place and centered on the support H by the dogs h' h', operated by means of the screw-shaft h² and crank h³. It is then raised to 130 the required height by means of the crank I', and held at that elevation by the ratchet-wheel I² and pawl i. The driving-shaft F is

set in motion and imparts, through the crank-wheel f and pitman f' , a vibratory movement to the saw-frame and a curvilinear reciprocating movement to the saw E. At the same time, acting through the eccentric f^2 and connecting-rod m' , the driving-shaft imparts a vibratory movement to the pawl-carrier N, which produces an intermitting rotation of the ratchet-wheels L L and of the adjacent pair of chain-wheels K K, geared therewith. The chains k k , acting through the block g^3 and slotted arm g^2 , move the carriage G and support H intermittingly in one direction on the ways g g , till the shaft k' , carrying the block g^3 , passes around the chain-wheels at one end of the machine, when the movement of said carriage is retarded and momentarily arrested. Returning on the opposite side of the chain-wheels, the block g^3 moves the carriage in like manner in the reverse direction. The saw-frame engaging by its arms b b the patterns D' D', causes them and the cross-heads D D, to which they are attached, to vibrate therewith on the shaft A. At the same time said cross-heads and patterns are moved with the carriage lengthwise of said shaft by means of the standards g' g' . As the saw-holding blocks C C are moved upwardly in the slotted arms b b by the longitudinal movement of the patterns D' D', they approach each other and the curvature of the saw E is consequently increased, and vice versa. The curved flanged patterns D' D', engaging the T-grooves in the blocks C C, turn the same as they pass through them and maintain the blade of the saw at an inclination crosswise corresponding to the inclination of that portion of the curved faces of said patterns in contact with said blocks C C, thus causing the saw to produce a cut varying in curvature in the direction of the saw-stroke and corresponding in curvature in the direction of the feed to the curvature of the patterns. The saw having teeth on both edges, the block is raised an interval, as described, at each reversal of the movement of the carriage, and a stave of section is cut by the movement of the carriage in each direction.

It is obvious that a great variety of curved surfaces suitable for various articles may be produced by changing the contour of the patterns D' D', which may be formed on any desired curve or combination of curves.

The arms b b should be set at the required angle to hold the cutting-edges of the saw as it approaches or recedes from the axis of oscillation in arcs of concentric circles, the centers of which are in said axis of oscillation of the saw-frame. When the ends of the saw are brought nearer to each other to produce a kerf of smaller radius, it is obvious that the middle of the blade will be lowered relatively to its ends, and for this reason the longitudinal curve of the cut will not be as sharp toward the ends as the curvature of the guides. Consequently, to produce a cut of a given longitudinal curvature, the guides must be

formed on a gradually-increasing curvature toward the ends. The saw is caused to bend in its various positions to the required arcs by making it a little more flexible at the ends and allowing it to turn freely at the ends on the cylindrical bearings e e. When the saw is turned by the guides to cut upward or downward, the upper edge, being nearer the axis of oscillation, will be bent to the arc of a smaller circle; but as each longitudinal section of the saw-blade arrives at any point in the cut it will assume the curve to which the cutting-edge was bent at that point. If the cutting-edges of the saw are maintained in arcs of concentric circles, its ends will describe in their movement toward and from the axis of oscillation lines curved slightly outward at the middle; but the deviation from straight lines is so slight that in practice it may be generally, if not always, disregarded and the arms b b made straight.

I claim—

1. In a machine for producing a cut of variable curvature, the combination of a flexible saw or cutter and means of changing its curvature while it is making a cut, substantially as and for the purposes set forth.

2. In a machine for producing a cut of variable curvature, the combination of a flexible cutter, holders supporting the cutter on opposite sides of the work, and mechanism connected with and arranged to change the distance between said holders while the cutter is in operation, substantially as and for the purposes set forth.

3. In a machine for producing a cut of variable curvature, a flexible cutter, means for changing its curvature while in operation, and a pattern arranged to change the direction of the cut transversely to the direction of the stroke of the cutter, substantially as and for the purposes set forth.

4. In a machine for producing cuts of variable curvature, a flexible cutter, means for changing the curvature of said cutter when the same is in operation, feeding mechanism, and mechanism for changing the position and inclination of the cutter with reference to the line of feed, substantially as and for the purposes set forth.

5. In a machine for producing a cut of irregular or variable curvature, the combination of a flexible cutter, feeding mechanism, saw-holding devices and guides arranged to change the curvature of the cutter, and a pattern arranged to change the position of the saw, whereby its curvature is changed and at the same time the line of its cut in the direction of the feed is determined, substantially as and for the purposes set forth.

6. In a machine for producing a cut of irregular or variable curvature, the combination, with a vibratory saw-frame provided with inclined guide-arms, saw-holding blocks held to said arms, a flexible saw secured to said blocks, and mechanism arranged to move said blocks lengthwise of said arms, whereby

the curvature of the saw is changed, substantially as and for the purposes set forth.

7. In a machine for producing a cut of irregular or variable curvature, the combination of a vibratory saw-frame, a flexible saw held in said frame, and a pattern arranged to move said saw while the same is in operation toward or from the center on which said frame vibrates, substantially as and for the purposes set forth.

8. In a machine for producing a cut of irregular or variable curvature, the combination of a vibratory saw-frame having slotted arms, saw-holding blocks held and capable of turning in said arms, a saw secured to said blocks, and curved patterns engaging with said blocks and arranged to move and turn the same in said arms in conformity with the curvature of the cut to be produced, substantially as and for the purposes set forth.

9. In a machine for producing a cut of irregular or variable curvature, the combination, with a vibratory saw-frame having movable saw-holding blocks, of means for moving said blocks toward or away from each other, and a flexible saw secured at the ends in cylinders which have bearings and are capable of turning in said blocks, substantially as and for the purposes set forth.

10. In a machine for producing a cut of irregular or variable curvature, the combination of a vibratory saw-frame having inclined slotted arms, saw-holding blocks journaled in and movable lengthwise of said arms, a flexible saw secured at the ends in cylinders which are held and are capable of turning in transverse holes in said blocks, and curved patterns working longitudinally through transverse openings in said blocks, substantially as and for the purposes set forth.

11. In a machine for producing a cut of irregular or variable curvature, a fixed shaft, a vibrating saw-frame mounted thereon and having inclined arms, saw-holding blocks carried by and movable lengthwise of said arms, a flexible saw secured at the ends to said blocks, vibrating cross-heads mounted on said shaft on opposite sides of said saw-frame, patterns attached to said cross-heads and movable lengthwise in engagement with said blocks, and a carriage movable parallel with said shaft and connected with said cross-heads, substantially as and for the purposes set forth.

12. In a machine for producing a cut of irregular or variable curvature, the combination of a flexible saw or cutter, means for changing the curvature of said saw while the same is in operation, a carriage movable on suitable ways, chain-wheels carrying parallel chains, and a cross-shaft attached to said chains and connected with and movable

lengthwise of an arm attached to said carriage perpendicular to its line of travel, substantially as and for the purposes set forth. 65

13. In a machine for producing a cut of irregular or variable curvature, the combination of a vibrating saw-frame having inclined arms, a flexible saw having sliding connections with said arms, a carriage capable of rectilinear movement transversely to the stroke of said saw, mechanism for feeding said carriage and curved patterns connected with said carriage and saw-frame so as to partake of the movements of each, and also connected with the ends of the saw so as to move the same lengthwise of the inclined arms of the saw-frame, and thereby produce a greater or less curvature of the saw, substantially as and for the purposes set forth. 75 80

14. In a machine for producing a cut of irregular or variable curvature, a vibrating saw adjustably held therein, guides arranged to change the curvature of the saw while the same is in operation, a work-support, feeding mechanism for moving said support transversely to the stroke of the saw, and mechanism for moving said support transversely to the feed toward and from the plane of the saw, substantially as and for the purposes set forth. 90

15. In a machine for producing a cut of irregular or variable curvature, the combination of a vibrating saw-frame having inclined arms, a flexible saw held at the ends in blocks 95 so as to turn therein on axes transverse to its blade, said blocks being attached to and movable lengthwise of said inclined arms and capable of turning, a carriage movable transversely to the saw, and curved patterns connected and movable with said carriage and saw-frame and provided with flanged edges which engage with undercut grooves in said saw-holding blocks, substantially as and for the purposes set forth. 100 105

16. In a machine for producing a cut of irregular or variable curvature, the combination of a flexible saw or cutter, a work-support, mechanism for moving the same past the saw, a pattern which determines the direction of the cut in the line of the feed, and mechanism arranged to increase or diminish the curvature of the saw in the direction of its stroke, according to the curvature of the cut in the line of feed, substantially as and 110 115 for the purposes set forth.

In testimony that I claim the foregoing as my own I affix my signature in presence of two witnesses.
